UNITED STATES PATENT OFFICE.

NATHANIEL G. WARTH, OF GALLIPOLIS, OHIO.

TELEPHONE REPEATER APPARATUS.

937,901.

Specification of Letters Patent. Patented Oct. 26, 1909.

Application filed December 20, 1907. Serial No. 407,314.

To all whom it may concern:

Be it known that I, NATHANIEL G. WARTH, a citizen of the United States, residing at Gallipolis, in the county of Gallia and 5 State of Ohio, have invented a certain new and useful Improvement in Telephone Repeater Apparatus, of which the following is a specification.

This invention relates to an improved telephone-current repeater apparatus for location or connection at an intermediate point or series of such points in a telephone main line circuit.

The invention is directed more particularly to an instrument adaptable to service of various conditions, as, for example: (1) in reciprocally operating repeater systems of the type described in United States Patent No. 845,282, issued to me February 26, 10 1907, and also in Patent No. 864,713, of the same country, issued to me August 27, 1907, in which but one repeater instrument is necessary and the retransmission from it is divided, being bi-directional or impressed 15 upon both line circuits simultaneously; (2) in reciprocally operating systems of the type described in patent of the United States No. 850,079, issued to me April 9, 1907, and in a modification of the same general type of 20 system for which Letters Patent of the United States was applied for by me on July 12, 1907, S. No. 383,883, and in which two repeater instruments are necessary for 25 reciprocal repeating and the retransmission 30 from them is uni-directional or impressed upon the lines progressively only; and (3) in a system for which I have applied for Letters Patent of the United States on April 22, 1907, S. No. 369,524, in which system two 35 repeater instruments are also necessary for 40 securing the reciprocal retransmissions, and in which the retransmission is also in but one direction from each transmitter, but in which both repeaters operate to retransmit 45 into their respective lines simultaneously.

The application for the present patent is, as to some of its features, a division of my said application for patent filed July 12, 1907, S. No. 383,883.

50 The repeater contemplated herein becomes adaptable to the various types of systems, or service referred to, by utilizing it in single or in double units according to the system,

and by changing the windings or connections thereto to meet the particular or respective use, according to the requirements of the inventions shown in the patents and applications to which reference has been made.

The chief object of the present invention 60 is to produce an instrument of improved form and of greater sensitiveness and efficiency, thus securing more positive and reliable operation, as will be particularly explained herein and delineated in the drawings.

The repeater, as herein shown, comprises two principal elements, namely, a magnetically sensitized electro-magnetic receiver and a variable resistance transmitter, arranged 70 or assembled in repeater-relation.

The invention consists in the form and arrangement of detail members and parts entering into the organization and association of the principal elements.

The particular form and arrangement of the several parts forming this particular embodiment of the invention, as set forth herein, may be varied without departing from 75 the scope and spirit of the invention.

The dimensions of the several members, parts and adjustments may be varied, it sufficing to state that the entire apparatus, particularly as to the moving and mobile parts and members, as will be readily understood by those skilled in the art, should be of substantial yet delicate construction, so as to secure maximum possible results and efficiency with a working force so minute and transitory or fugitive as a telephone current 80 enfeebled or attenuated by long or difficult transmission.

In the accompanying drawings—Figure 1 is a front elevation or plan view, according to its position in use, partially in section, of 95 my repeater instrument comprising a receiver and a transmitter assembled in repeater relation; Fig. 2 is a view in side elevation, partially in section, of the repeater instrument; Fig. 3 is an end view, also partially in section, of the same instrument. This view represents the top or transmitter end of the apparatus and is particularly directed to the support for the transmitter; Fig. 4 is an end view of the receiver proper, 100 representing the same viewed from the trans-

mitter end of the instrument and showing the mounting and arrangement of the pole pieces and magnet spools and also the location of the wedge-shaped armature, which is indicated in dotted outline in front of the poles; Fig. 5 represents an adjustable furcular arm for supporting the transmitter; Fig. 6 represents a front view of the common receiver-transmitter diaphragm or armature-electrode, which carries on its front the wedge-shaped armature and on its back the principal electrode of the transmitter; Fig. 7 represents one of the soft iron cores and pole pieces of the receiver with its beveled 10 polar surface, which is adapted to use with the wedge or V-formed armature; Fig. 8 illustrates the wedge or V-formed armature, viewed endwise, and the opposed beveled poles, with lines drawn to indicate the magnetic flux space and the extended space for the armature movement.

In Fig. 1 the receiver T and transmitter M are preferably arranged in vertical position with the transmitter above the receiver. 25 From the construction shown it will be obvious that the instrument may be placed in any position, but the preferred position is with the diaphragm horizontally disposed, thereby permitting the carbon granules to 30 arrange themselves loosely and practically uniformly as to density throughout the mass. This position avoids the tendency on the part of the granules of carbon to pack or become compressed, which is frequently the 35 case in the instruments having a vertically positioned diaphragm and carbon chamber. A "packed" transmitter element fails to respond to minor or delicate impulses on its diaphragm, and such a state of imperfection 40 in a repeater renders it impracticable, or at least unreliable, and is especially to be avoided. The conditions conducing to the packing also restrain the diaphragm or vibrating member of the transmitter from 45 free and proper movement. These conditions are the effect of gravity and the pocket form of the lower side of the carbon chamber, a combination preventing a full and free movement of the carbon granules when 50 the diaphragm presses inward or moves outward. As in the view, with the diaphragm D arranged horizontally, the granules lie loosely and evenly distributed on its upper surface and are not forced into a confining 55 "pocket" which tends to render the properly mobile parts immovable. In the vertical arrangement of the repeater the movements of the diaphragm agitate almost the entire body of the freely movable granules. 60 The granules not participating in the vibrations lie around the square lower corner of the carbon granule chamber A and are utilized to preserve a constant closed circuit, necessarily of comparatively high resistance, 65 for the transmitter when the front or prin-

cipal carbon electrode E is vibrated vigorously.

Two other factors are combined with the above means to prevent the "packing". First, the upper corner K of the granule chamber is curved as is also the shoulder of the chamber next the upper carbon electrode E². This electrode E² has either a curved or beveled edge and is of circular form. The second factor is the constant elimination of the carbon-dust produced by attrition or abrasion between the granules. This dust when permitted to accumulate settles to the bottom of the chamber forming a compact mass or cake of comparatively low resistance 80 which is sifted out of the chamber through very small perforations O in the diaphragm, as shown more clearly in Fig. 6. The electrode E is similar to electrode E², but has a somewhat larger electrode-surface and also 85 has a beveled or rounded edge and is also of circular or disk-like form. The circular supporting stud S for electrode E is shown to have a beveled edge. This construction or formation of the carbon chamber provides 90 means for the easy movement of the granules when disturbed by the diaphragm, and the movement conduces to effect a circulation of the granules within the chamber, such movement or circulation being from the center of 95 the chamber, or from the upper electrode, outward at the top of the mass and in reverse order at the bottom of the mass.

In practice the chamber should not be more than three-fourths filled with the 100 granules, as indicated at F, so that they may have ample room for free movement. The sides and curved top of the chamber should be plated with gold to provide a smooth non-corrosive surface and maintain constantly good connection with the granules. The upper or rear carbon-electrode E² may be dispensed with and an adjustable plug J, correspondingly formed and plated with gold at its tip, used in its stead. The diaphragm D is of suitable non-conducting material, for example, mica, but the diaphragm may be of a conducting substance, in which event it should be insulated from the containing case M⁴. The diaphragm 110 may also be of magnetic substance and directly serve as an armature to the poles T⁵ of the receiver T. A preferred arrangement of armature is shown at T⁶ in Fig. 1 and further illustrated in Figs. 2, 4, 6, and 120 8. The armature T⁶ is of rectangular outline as viewed at its back (see the dotted outline in Fig. 4). The ends of this armature are squared with the back, and the sides 125 may be triangular, or the front edge may be flattened as indicated, being formed, in cross section, similar to a blunt wedge or a flat pointed V. The armature T⁶ may be attached directly to the diaphragm D but is 130

preferably mounted on the stud S with the electrode E, but on the opposite side of the diaphragm and on the opposite end of the stud S.

- 5 To avoid injury to the transmitter in attaching and detaching the armature, an intermediate threaded nut or bur T⁷ is placed on the stud between the armature and the diaphragm to firmly clamp the diaphragm 10 between it and the head of the stud, which latter is within the carbon-chamber. To adapt this form of beveled armature to the poles T⁸ of the receiver T, the poles are correspondingly beveled as shown in Figs. 1, 15 2, 4, 7, and 8. The pole pieces T⁵ are integral with the soft iron extension cores T⁹ of the receiver T, as is more clearly shown in Fig. 7. An advantage of this form of armature and pole or pole pieces resides in 20 the securing of a relatively extended armature movement with a very close adjustment or very small flux space or air-gap between the armature and its attracting pole or poles, without subjecting the members to 25 actual contact. This is illustrated in Fig. 8, where the line or mark T⁹ designates a magnetic flux line or the length of the air-gap between pole and armature, and the line or mark T¹⁰ designates the length or range 30 of movement of the armature and the direction thereof. The length of the movement with the same proximity of the armature to the polar surface can be increased by making the slant or pitch of the bevel more 35 abrupt. The diagonal polar surface has the added advantage of increasing the area of the opposed polar and armature surfaces and augmenting the efficiency of the magnetic circuit.
- 40 To secure the best results for an arrangement of armature and two poles, as shown, the air-gaps on both sides of the armature should together be considerably less than the distance directly between the poles.
- 45 Where this form of armature is used with one pole, the pole should be V-shaped to conform to the bevel on each side of the armature. The helices T³ and T⁴ of receiver T are wound on the soft iron extension cores 50 T⁸ to the permanent magnet T¹¹, thus establishing a constant residual magnetic stress or sensitization of the vibratory armature-electrode T⁶-E. The helices are shown (in Fig. 1) to correspond with the circuit arrangement designated and illustrated in one of my systems referred to, but may be otherwise wound and variously associated with my repeater circuits as required. The terminals of the helices are brought out or 55 connected to their respective binding-post connections T¹². The receiver T is mounted upon non-magnetic blocks or pedestals T¹³ and T¹⁴ and is held in position by metal clamps T¹⁵. The non-magnetic pedestals 60 are mounted upon the base Z, being attached

thereto by screws inserted from below the base. A manually-adjustable "keeper" or magnetic shunting block of iron I is pivotally supported in a recess I² at the top of the front non-magnetic pedestal supporting the receiver T. This keeper is pivotally controlled in its position by the screw I³ passing out through the end of the non-magnetic pedestal, and when raised between the limbs of the permanent magnet of receiver 75 T will shunt more or less of the permanent flux lines, according to its position, thus providing a simple method of regulating the residual or sensitizing magnetic influence with reference to the armature T⁶. When 80 the keeper is permitted to contact, as indicated by the dotted outline thereof, with the rear ends of the extension cores T⁹, the attraction of the permanent magnet for the armature T⁶ is at a minimum.

85 It will be appreciated by those skilled in the art that it is very difficult in practice, or manufacture, to secure permanent magnets of uniform strength, or to have them of a certain desired strength and for use in an 90 instrument as delicately constituted as a telephonic relay. The magnets usually have an excessive strength or attractive effect on the transmitter armature, hence it is advantageous that they be provided with some 95 means of adjustment to vary their attraction on the transmitter. This is so, for the reason, that the electro-magnetic effects on the transmitter are very weak at best, and a surplus permanent magnet effect so overpowers them that the transmitter is affected only slightly or not at all. The permanent magnetic attraction should in each case be independently controllable so that it may be nicely proportioned to the electro-magnetic 100 effects, to enable the armature of the transmitter to be vibrated with the entire force of the electro-magnet under the influence of the received currents, and it is important 105 that the electro-magnet have its maximum 110 effect.

115 The magnetic shunting arrangement permits of a nicely adjustable sensitizing effect upon the armature-diaphragm I⁶-D to secure maximum sensitiveness and co-operative 120 action with the received telephonic currents, preventing the reduction of same by a disproportioned stress or improper ratio of magnetic effects on the diaphragm. The binding-posts are insulated from the base Z 125 by bushings and the connections are passed through the base by means of insulating tubes or bushings, as shown in Figs. 1, 2, and 4. The transmitter is pivotally supported on base Z by the pedestal M⁶, which is bolted to the base, as shown in Fig. 2. The pedestal has two lugs or prongs M⁷, see Fig. 3. Between the prongs is placed the adjustable arm M⁷ provided with a 130 forked extension, to the ends of which is

affixed a ring M^8 , the transmitter case M^4 being attached thereto by screws. The adjustable arm M^7 is also provided with an elongated aperture M^{10} , Fig. 5, through which, as well as through the lugs M^6 , a screw-bolt M^9 passes. The elongated aperture M^{10} permits of a forward and backward adjustment of the transmitter M with its diaphragm-armature T^6 — D with reference to the poles T^5 of receiver T .

A set-screw M^{16} , Figs. 1, 2, 3 and 5, is inserted through the rear portion of the arm M^7 so as to protrude into the aperture M^{10} against the screw-bolt M^9 , thus permitting a secondary adjustment and providing a stop for the armature with reference to the receiver and preventing actual contact of the armature with the magnet, hence avoiding, in the adjustment of the members with relation to each other, violent stresses of the delicate diaphragm. The arm M^7 is held in proper place between the lugs M^6 by the screw-bolt M^9 , Fig. 3, said screw-bolt also extending through the two washers M^{11} and the thumb-nut M^{12} . The loosening or tightening of the thumb-nut permits the arm to be moved and "set" in any of its desired positions. The arm M^7 can swing around the screw-bolt pivot through an arc of more than half a circle, say 270 degrees, thus permitting the transmitter to be readily turned into an inverted position for inspection and repair without disturbing the receiver or disconnecting the parts.

The casing M^4 of the transmitter forms one of the transmitter terminals for connecting the transmitter in its primary or battery circuit. This connection is made through the arm M^7 , the pedestal M^5 , base Z and binding-post M^{13} . The other terminal of the transmitter is the electrode E , to which the flexible conductor M^{14} is connected and conducted to the insulated binding-post M^{15} . For clearness, this connection is shown (see Figs. 1 and 2) wired through the base Z and carried to the binding-post M^{15} in the manner illustrated with reference to connecting the receiver terminals. This connection should, however, be made through a flexible conductor carried back over the supporting pedestal to permit the transmitter to be free to swing upward on its trunnion. The adjustable plug J carrying the top or rear carbon electrode E^2 is adapted, as a screw-piston, to regulate the resistance of the transmitter by raising and lowering the level of the carbon-granules in the chamber and also by varying the distance between the two electrodes. The diaphragm or vibrating armature-electrode D — E is fastened at its periphery to the case M^4 by the ring M^8 , which is provided (as is also the front portion of the case) with screw-threads for the purpose.

The repeater as described above can be provided with the protective casing or cover

Y , shown in Figs. 2, 3, and 4, which as shown is of semi-cylindrical form having flat ends. The cover is supported in position by the bead or flange Z^2 that extends around the edge of its base just beyond its bottom. The spring Y^2 , attached to the case and extending into the base at the bottom of the cover, retains the cover in place at its lower end, while spring Z^3 , attached to the base Z and forming a catch with the projection or ear Y^3 , retains the cover in place at its upper end. The cover is provided with apertures Y^4 at each end to permit the passage of the circuit terminals to their respective binding-posts.

What I claim and desire to secure by Letters Patent is:

1. In a telephone repeating device, a transmitter including a case and a vibrating diaphragm united to form a granule-containing chamber, an electrode on the diaphragm projecting into said chamber, the wall of said chamber that opposes said diaphragm being concavely curved and having a re-entrant center forming an electrode, whereby free movement of granules within the chamber is promoted and packing thereof prevented.

2. In a telephone repeating device, a transmitter including a case and a vibrating diaphragm united to form a granule-containing chamber, an electrode on the diaphragm projecting into said chamber, the wall of said chamber that opposes said diaphragm being concavely curved and having a re-entrant center, and an adjustable electrode on said re-entrant center, substantially as described.

3. In a telephonic repeating device, in combination, a transmitter and an adjustable and oscillatory arm or support upon which the transmitter is mounted, a support for said adjustable arm, and a base to which the support is attached, whereby the transmitter may be adjusted to its receiver.

4. In a telephone repeater relay, the combination with a base or support, of an electro-magnetic receiver and a resistance-varying transmitter, confronting each other in repeater relation, a permanent-magnet for sensitizing the receiver, and means associated therewith for regulating its effect upon the transmitter, bevel-faced poles for the receiver, an adjustable and pivotal arm carrying the transmitter, and a single diaphragm interposed between the transmitter and the receiver, said diaphragm bearing an armature having bevel-faced polar-facing surfaces corresponding to the beveled magnet poles, substantially as shown and described.

5. In a telephone repeater relay, the combination with an electro-magnetic receiver and a resistance-varying transmitter confronting each other in repeater relation, a common diaphragm interposed between them, an adjustable rear-electrode to vary

the normal resistance of the transmitter, an
adjustable and oscillatable support for the
transmitter for varying the normal relation
between the transmitter and the receiver, and
5 independent means for varying the normal
attraction of the permanent-magnet upon
the armature whereby a regulable ratio of

the permanent-magnetic effect to the electro-
magnetic effect are obtained.
